(57) **CLAIM**

The ornamental design for a trailer hitch receiver cover, as shown and described.

DESCRIPTION

FIG. 1 is a perspective view of a trailer hitch receiver cover showing my new design;

FIG. 2 is a right side elevational view of thereof, all sides being identical;

FIG. 3 is a front elevational view thereof; and,

FIG. 4 is a back plan view thereof.

The broken lines shown in the drawing are environmental only and form no part of the claimed design.
